UNITED STATES PATENT OFFICE.

JAY REED, OF FREEMAN, MISSOURI.

BUCKLE.

SPECIFICATION forming part of Letters Patent No. 439,254, dated October 28, 1890.

Application filed February 24, 1890. Serial No. 341,490. (No model.)

To all whom it may concern:

Be it known that I, JAY REED, a citizen of the United States, residing at Freeman, in the county of Cass and State of Missouri, have 5 invented certain new and useful Improvements in Buckles, of which the following is a full and clear description, reference being had to the accompanying drawings, forming part of this specification, in which—

10 Figure 1 is a plan view showing the top side of the buckle with the strap attached. Fig. 2 is a side elevation. Fig. 3 is an elevation of the opposite side. Fig. 4 is the same view with a strap attached.

15 My present invention relates to a new and useful improvement in harness-buckles; and it consists in the combination and arrangement of parts hereinafter explained, and specifically pointed in the claims.

20 To enable others skilled in the art to make and use my invention, I will now describe its construction and indicate the manner in which I carry the same out.

In the drawings, A represents the body of 25 a buckle, provided with the tongue B. This tongue is formed of a single piece of wire or metal, one end of which is bent around one corner of the body, as shown at a in Fig. 1. The wire is then carried forward to the opposite end of the body at b to form the tongue, 30 where it is bent back upon itself some distance, and is then passed to the opposite corner of the buckle, as shown at c in Fig. 1, where it is again passed around the body of the buckle, and at right angles crossing the wires, as shown at C in Fig. 1, and the end loosely secured around the body at d, thus forming not only a loop for holding down the end of the harness-strap, but also a lever for

raising up the tongue by a simple pressure of 40 the thumb when it is desired to unbuckle the strap. It is evident that by this construction I save the expense of the usual leather loop on harness. Again, it is evident that by thus forming the tongue of the buckle so that the 45 strap D will pass and fit between the coils I avoid the necessity of punching or cutting the strap to allow a passage for the tongue to pass through, as in the case of the ordinary buckle.

Having thus described my invention, what 50 I claim as new, and desire to secure by Letters Patent, is—

1. In a buckle, the combination, with the body portion, of a combined tongue and lever formed of a single piece of wire, one end of 55 which is coiled upon the rear cross-bar of the body portion and carried across and above said cross-bar to form a lever, and also a loop for the strap, and thence coiled around the cross-bar at that end and curved inward and 60 forward and back upon itself to the cross-bar to form the tongue proper, substantially as herein described.

2. In a buckle, the combination, with the body portion, of a wire tongue whose opposite sides are pivotally mounted upon the opposite ends of the cross-bar of the body portion and thence converge toward the front of said body portion, said wire having one of its ends carried upward and above the cross-bar 65 to form a loop, which also serves as a lever to 70 raise the front of the tongue, substantially as herein described.

JAY REED.
